UNITED STATES PATENT OFFICE.

THOMAS MANAHAN, OF NEW YORK, N. Y.

INSECTICIDE COMPOSITION.

SPECIFICATION forming part of Letters Patent No. 399,999, dated March 19, 1889.

Application filed January 19, 1889. Serial No. 296,881. (No specimens.)

To all whom it may concern:

Be it known that I, THOMAS MANAHAN, a citizen of the United States, residing at New York, in the county and State of New York, 5 have invented new and useful Improvements in Compositions for Treating Paper and other Fabrics, of which the following is a specification.

The object of this invention is a composition which is intended particularly to render paper moth-proof, but which may be used with advantage for treating other fabrics, such as muslin or cloth.

In carrying out my invention I take naphthaline—such as known in the trade as “sublimed naphthaline”—and melt the same, by preference, in a water-bath to the consistency of a watery liquid. To one gallon of this melted naphthaline I add about one ounce of 15 glycerine and about one-half ounce of essence of mirbane. After the composition has been prepared, and while the same is kept hot enough to retain it in a liquid condition, the paper or other fabric is immersed therein 20 for a sufficiently long time to permit the liquid to saturate the body of the fabric. The saturated fabric is then withdrawn from the liquid composition and immersed in cold water. When the fabric is withdrawn from the water, it appears in the form of a white 30 crystallized sheet, which is pliable and not liable to crack when bent or rolled, such pliability being insured by the action of the glycerine. The essence of mirbane is added, because this substance is poisonous to vermin 35 and tends to keep them off.

What I claim as new, and desire to secure by Letters Patent, is—

A composition for treating paper and other fabrics, which consists of naphthaline, glycerine, and essence of mirbane, about in the proportions hereinbefore set forth. 4c

In testimony whereof I have hereunto set my hand and seal in the presence of two subscribing witnesses.
